UNITED STATES PATENT OFFICE.

ROLAND B. DAY, OF SWARTHMORE, PENNSYLVANIA, ASSIGNOR TO ALFRED B. ADAMS,
OF NEW YORK, N. Y.

APPARATUS FOR THE TREATMENT OF HYDROCARBON OILS.

1,357,278.

Specification of Letters Patent.

Patented Nov. 2, 1920.

Application filed July 30, 1918. Serial No. 247,394.

To all whom it may concern:

Be it known that I, ROLAND B. DAY, a citizen of the United States, residing at Swarthmore, in the county of Delaware and 5 State of Pennsylvania, have invented new and useful Improvements in Apparatus for the Treatment of Hydrocarbon Oils, of which the following is a specification.

This invention relates to apparatus for the 10 treatment of hydrocarbon oils and pertains particularly to a combined apparatus for extracting oil from shale or similar hydrocarbon oil containing material and for cracking the oil so extracted.

15 The invention includes the apparatus for treatment of the shale and the oil extracted therefrom by contact with hot gases of combustion whereby oil vapors are drawn from the shale and certain of the vapors are condensed and are led back again to the shale and subjected therein to a cracking temperature.

One feature of the invention is the apparatus for the fractional condensation of the 25 oil vapors driven from the shale, and the means for the progressive introduction of the fractions into contact with the now semi-spent shale and gases of combustion in such a manner that the lightest fractions 30 are treated with the hottest gases and the heavier fractions are treated with the progressively cooled gases and the shale at a point more remote from the source of the gases.

35 The apparatus is designed to perform distillation and cracking operations at a common pressure and is operated at certain ranges of temperatures for the cracking.

The invention further provides apparatus 40 for the generation of gases of combustion adjacent the base of the combined distilling and cracking chamber which is to operate filled with shale, and also for the fractional condensing of oil vapors in a tower located 45 above and in continuation of the cracking chamber.

The invention also provides apparatus including mechanically operated valves for controlling the movement of the shale into 50 and out of the apparatus and the maintaining of a constant pressure.

The above mentioned and other features of the invention will be described in detail and claimed in the following specification 55 and claims and described in the drawings, in which:

Figure 1 represents a vertical sectional view through the preferred form of apparatus;

Fig. 2 is an exterior view taken at right 60 angles to Fig. 1 and illustrating the progressive arrangement of the piping for the fractionally condensed oil.

It is generally known that different oils will crack at different temperatures and that 65 in the case of petroleum the lower the boiling point the higher the cracking point. The present invention provides for the application of this principle to the extraction and cracking of hydrocarbon oils while in a 70 vaporous condition by contact with hot gases of combustion substantially devoid of oxygen or by other heating means. In carrying the process into effect, the oil to be treated is first separated into a number of 75 different cuts or fractions according to their boiling points and thereafter acted upon by the temperature best suited to each fraction.

The invention provides an apparatus 80 which is substantially tower-like or cylindrical.

In the lower part of this tower, which is 85 preferably of metal, is a lining of firebrick. This portion constitutes a combined distilling and cracking chamber and is to be maintained full of shale. Gases of combustion are generated and directed into the shale near the base of the mass in the tower providing the heat and pressure necessary for 90 cracking. The upper portion of the apparatus constitutes a fractionating cooling chamber and need not be lined with fire brick as the heat is not as intense and no cracking 95 will take place here. A hopper is provided above the tower for fresh shale and valves at the top and bottom of the tower control the admission of the fresh shale into the tower and the discharge of the spent shale at the lower end. The shale admitted in the 100 top drops into the lower part of the tower, substantially filling the distilling and cracking chamber. Attached to the inner surface of the walls of the cooling chamber is a series of annular troughs adapted to catch 105 condensates of different boiling points. A corresponding set of pipes conduct the material thus caught below to the cracking chamber where it comes into contact with the heated shale and is vaporized again and 110 cracked. The cooling chamber may have its walls cooled by any suitable means.

- Referring in detail to the drawing, 1 indicates a cylindrical metal casing which stands vertically on any suitable foundation, not shown. The lower half of the interior of the casing 1 is the combined distilling and cracking chamber and because it is subjected to very intense heat, it is lined with fire brick 2 or other material capable of withstanding cracking temperature.
- 10 The lower end of the cylinder is continued downwardly in a tapered portion 3. The upper end of the cylinder 1 is closed by a top member 4 and just below the top is an outlet opening 5 for the passage of vapors
- 15 which may be driven off to a suitable condenser, not shown. Adjacent the bottom of the cylinder 1 and above the tapered portion 3 are the laterally extending conically shaped hollow burner extensions 6. These
- 20 extensions are tightly secured to the cylinder 1 and are a substantially continuous part thereof. Fire brick 2 is also used within the burner extensions 6. At the extreme ends of the extensions 6 and positioned just
- 25 within the bore of the extensions is an oil burner 7 having connected thereto the oil pipe 8 and steam pipe 9. The fire blast from the burner 7 may create considerable pressure, causing a positive movement of gases
- 30 upward through the cylinder 1. An elbow pipe 10 of approximately the same bore as the bore of the extension 6 is fastened to the extension over the end of the bore and extends downwardly. Oxygen or air under
- 35 pressure may be supplied through the pipe 10 from any suitable source, such as a pump, not shown. The end of the pipe 10 farthest removed from the towers is preferably provided with valve means for closing the same and thus maintaining pressure
- 40 within the tower.
- Mounted on the top 4 is a hopper 11 adapted to hold the untreated shale. Between the hopper 11 and the top 4 is a measuring valve 12 illustrated as being a tapered rotary valve having the casing 13. A spring 14 is adapted to hold the valve tightly seated. It is necessary that there be a tight connection at this point as the apparatus is designed to operate under pressure. The rotary valve post 12 is recessed on one side so as to permit a given amount of shale to enter the chamber through the opening 15 when the valve is rotated.
- 45 A rolling grate 16 is illustrated as extending across the cracking chamber at a point just below the burner extensions 6. Power is applied to the grate 16 by means of a driven wheel 17.
- 50 A vertical grate member 18 is provided to prevent the shale from falling into the burner extensions 6 and is designed to permit the passage of gases of combustion therethrough. Plungers 19 are illustrated
- 55 as mounted near the top of the cracking
- chamber and are adapted to be thrust into the chamber to determine the height of the shale therein. At the bottom of the apparatus and below the grate 16 is a discharge valve 20 similar to valve 12, having a casing 21 and spring 22. Drive wheels 23 are illustrated as connected to the valves 12 and 20 and are adapted to be connected to be a common source of power and so timed that the valves will be in the closed position during the same period in order that pressure may be maintained within the apparatus.
- 60 A plurality of annular collector flanges 24, 25, 26 and 27 are mounted around the interior wall of the upper portion of the cylinder 1 and serve to catch any material condensing on the inner surface. Material thus caught is led from the flanges 24, 25, 26 and 27 and through pipes 24^a, 25^a, 26^a, 85 and 27^a back into the cracking chamber and into contact with the shale. The flanges may be located at any suitable location according to the fractions to be obtained, fractions having low boiling points being caught 90 at the top of the chamber in flange 24 and conducted to that part of the cracking chamber having the temperature best suited for the cracking, which part is nearest the source of heat. Steam injector pipes 24^b, 95 25^b, 26^b and 27^b are provided at each point of introduction of the pipes 24^a, 25^a, 26^a and 27^a, respectively, to assist in forcing the oil into the mass of the shale within the tower. Below the burner extension there is provided a steam pipe 28 for injecting a blast of steam into the shale. An inspection plate 29 is provided on the tapered part 3 and an air pipe 30 is provided to furnish oxygen to burn out the carbon. In the usual operation the heat of the spent shale is sufficient to burn out the carbon.
- 65 In the operation of the apparatus, the shale is introduced from the hopper to fill up the cracking chamber. The burners 7 are ignited and the flames are projected toward the grates 18 and provide a current of intensely hot gases which pass through the grate member 18 and pass upwardly through the shale, distilling oil therefrom. The lighter vapors and gases pass out of the opening 5. The vapors condensing at the top of the cooling chamber are taken off through pipe 24^a, the next fraction through pipe 25^a, the next through pipe 26^a and 110 the lowermost fraction condensing at high temperatures just above the shale taken off through pipe 27^a.
- 70 Fraction No. 1 has a lower boiling point because it was heated by the coolest gases, 125 farthest from the burner. Accordingly in order that this distillate can be cracked, it must be subjected to the hottest cracking heat and it is therefore introduced by pipe 24^a at the lowermost point of introduction 130

- within the cracking chamber. Fraction No. 2 being taken from the flange 25 at a point farther down, by pipe 25^a is necessarily hotter and is led into the cracking chamber 5 above the first fraction. The effect is that the first introduction of oil into the hot gas and into the shale cooled it to the point where the next fraction would react to the best advantage.
- 10 Steam pipes 24^b, 25^b, 26^b and 27^b are indicated as being mounted at the lower points of introduction into the shale chamber of the pipes 24^a, 25^a, 26^a, and 27^a, respectively. The oil running in the pipes is thus blown 15 effectively into the shale and carried farther into the mass thereof than would be possible without the use of the steam blast.
- The cooling and fractionating tower is provided with a sprinkler ring 31 to furnish 20 water to run down and cool the upper part of cylinder 1. An oblique catch flange 32 encircles the cylinder at a point near the lower end of the cooling chamber and provides means for catching the cooling water.
- 25 A drain pipe 33 is connected to the flange 32 and provides for the discharge of the cooling water.
- The invention includes the operation at 30 temperatures ranging from 600° F. to 3000° F. and at pressure ranging up to 600 lbs. per square inch. Much of the shale now being treated could be used successfully without requiring a temperature above 1200° F. The apparatus must operate under pressure 35 and the pressure is equalized through the various pipes and other parts of the apparatus.
- Any number of fractions could be similarly obtained and treated by varying the number 40 and position of the collector flanges, and the apparatus is applicable to any type of shale or vapor phase process. Changes in size, shape and material may be made without departing from the scope of the invention.
- 45 I claim:
1. An apparatus for extracting hydrocarbon oils from shale and similar material and for treating the oils, which comprises a combined distilling and cracking chamber, a 50 cooling chamber positioned as a continuation of said combined distilling and cracking chamber, collector means within said cooling chamber for collecting materials condensed therein, means to admit shale into said distilling and cracking chamber, and means for generating hot gases of combustion and passing the same through said shale to distill and crack the oil therein.
  2. An apparatus for extracting hydrocarbon oils from shale and similar material and for treating the oils, which comprises a combined distilling and cracking chamber, a 55 cooling chamber positioned as a continuation of said combined distilling and cracking chamber, means to admit shale into said distilling and cracking chamber, and means for generating hot gases of combustion and crack the oil therein, and a plurality of 60 separate and independent means for conducting condensed oil from different parts of said cooling chamber and introducing said condensed oil into different parts of said distilling and cracking chamber and into contact with the shale material therein.
  3. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and introducing the same into said shale to distill and crack the oil therein, and a plurality of 70 separate and independent means for conducting condensed oil of different gravities from different parts of said cooling chamber and introducing said condensed oil into different parts of said distilling and cracking chamber.
  4. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and introducing the same into said shale to distill and crack the oil therein, and a plurality of 75 separate and independent means for conducting condensed oil of different gravities from different parts of said cooling chamber and introducing said condensed oil into different parts of said distilling and cracking chamber.
  5. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and supplying the same to said shale to distill and crack the oil therein, and a plurality of 80 separate and independent means for conducting condensed oil from different parts of said cooling chamber and introducing said condensed oil into different parts of said distilling and cracking chamber and into contact with the shale material therein.
  6. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, and means for generating hot gases of combustion and crack the oil therein, and a plurality of 85 separate and independent means for conducting condensed oil from different parts of said cooling chamber and introducing said condensed oil into different parts of said distilling and cracking chamber and into contact with the shale material therein.

ing chamber, means to admit shale into said distilling and cracking chamber, means for generating hot gases of combustion and supplying the same to said shale to distill and 5 crack the oil therein, means for collecting and conducting condensed oil from said cooling chamber at a point relatively distant from the source of said gases of combustion and introducing said condensed oil 10 into said distilling and cracking chamber at a point relatively adjacent the source of said gases of combustion, and means for collecting and conducting condensed oil from said cooling chamber at a point relatively nearer the source of said gases of 15 combustion than said first point of collecting and introducing the same into said distilling and cracking chamber at a point farther away from the source of said gases of combustion than the first mentioned point 20 of introduction.

7. An apparatus for extracting hydrocarbon oils from shale and similar material and for treating the oils, which comprises an 25 upright combined distilling and cracking chamber, a cooling chamber positioned as a continuation of said combined distilling and cracking chamber and immediately above the latter, collector means within said 30 cooling chamber for collecting materials condensed therein, means to admit shale into said distilling and cracking chamber, and means for generating hot gases of combustion and passing the same through said 35 shale to distill and crack the oil therein.

8. An apparatus for extracting hydrocarbon oils from shale and similar material and for treating the oils, which comprises an upright combined distilling and cracking 40 chamber, a cooling chamber positioned as a continuation of said combined distilling and cracking chamber and immediately above the latter, means to admit shale into said distilling and cracking chamber, means 45 for generating hot gases of combustion and introducing the same into said shale to distill and crack the oil therein, collector means within said cooling chamber to collect the oil condensed therein, and means to conduct liquid oil from said collector means to said 50 distilling and cracking chamber.

9. An apparatus for extracting hydrocarbon oils from shale and similar material and for treating the oils, which comprises an 55 upright combined distilling and cracking chamber, a cooling chamber positioned as a continuation of said combined distilling and cracking chamber and immediately above the latter, means to admit shale into 60 said distilling and cracking chamber, means for generating hot gases of combustion and supplying the same to said shale to distill and crack the oil therein, and a plurality of 65 separate and independent means for conducting condensed oil from different parts

of said cooling chamber, and introducing said condensed oil into different parts of said distilling and cracking chamber.

10. An apparatus for extracting hydrocarbon oils from shale and similar material and for treating the oils, which comprises an upright combined distilling and cracking chamber, a cooling chamber positioned as a continuation of said combined distilling and cracking chamber and immediately above the latter, means to admit shale into said distilling and cracking chamber, means for generating hot gases of combustion and introducing the same into said shale to distill and crack the oil 70 75 therein, collector means within said cooling chamber to collect the oil condensed therein, and means to conduct oil from said collector means and introduce it into said distilling and cracking chamber and into contact with the shale material therein. 80 85

11. An apparatus for extracting hydrocarbon oils from shale and similar material and for treating the oils, which comprises an upright combined distilling and cracking 90 chamber, a cooling chamber positioned as continuation of said combined distilling and cracking chamber and immediately above the latter, means to admit shale into said distilling and cracking chamber, means for 95 generating hot gases of combustion and supplying the same to said shale to distill and crack the oil therein, and a plurality of separate and independent means for conducting condensed oil from different parts 100 of said cooling chamber, and introducing said condensed oil into different parts of said distilling and cracking chamber and into contact with the shale material therein.

12. An apparatus for extracting hydrocarbon oils from shale and similar material and for treating the oils, which comprises an upright combined distilling and cracking chamber, a cooling chamber positioned as a continuation of said combined distilling and cracking chamber and immediately above the latter, means to admit shale into said distilling and cracking chamber, means for generating hot gases of combustion and supplying the same to said shale to distill 110 and crack the oil therein, means for collecting and conducting condensed oil from said cooling chamber at a point relatively distant from the source of said gases of combustion and introducing said condensed oil 115 into said distilling and cracking chamber at a point relatively adjacent the source of said gases of combustion, and means for collecting and conducting condensed oil from said cooling chamber at a point relatively nearer the source of said gases of combustion than said first point of collecting and introducing the same into said distilling and cracking chamber at a point 125 farther away from the source of said gases 130

- of combustion than the first mentioned point of introduction.
13. An apparatus for extracting hydrocarbon oil from shale and similar material and for treating the oil, which comprises a combined distilling and cracking chamber, a cooling chamber positioned as a continuation of said combined distilling and cracking chamber, collector means within said cooling chamber for collecting materials condensed therein, means to admit shale into said distilling and cracking chamber, and means for providing the sole source of heat comprising means for generating gases of combustion and intermingling the same with the shale within said distilling and cracking chamber to distill and crack the oil therein.
14. An apparatus for extracting hydrocarbon oil from shale and similar material and for treating the oil, which comprises a combined distilling and cracking chamber, a cooling chamber positioned as a continuation of said combined distilling and cracking chamber, means to admit shale into said distilling and cracking chamber, and means for providing a heating medium within said distilling and cracking chamber to distill and crack the oil therein, and a plurality of separate and independent means for conducting condensed oil from different parts of said cooling chamber and introducing said condensed oil into different parts of said distilling and cracking chamber.
15. An apparatus for extracting hydrocarbon oil from shale and similar material and for treating the oil, which comprises a combined distilling and cracking chamber, a cooling chamber positioned as a continuation of said combined distilling and cracking chamber, means to admit shale into said distilling and cracking chamber, and means for providing a heating medium within said distilling and cracking chamber to distill and crack the oil therein, means for collecting and conducting condensed oil from said cooling chamber at a point relatively distant from the source of said heating medium and introducing said condensed oil into said distilling and cracking chamber at a point relatively adjacent the source of said heating medium, and means for collecting and conducting condensed oil from a point relatively nearer the source of said heating medium than said first mentioned point of collection and introducing the same into said distilling and cracking chamber at a point farther away from the source of said heating medium than the first mentioned point of introduction.
16. An apparatus for extracting hydrocarbon oils from shale and similar material and for treating the oils, which comprises a combined distilling and cracking chamber, a cooling chamber positioned as a continuation of said combined distilling and cracking

chamber, means to admit shale into said distilling and cracking chamber, and means for generating hot gases of combustion and supplying the same to said shale to distill and crack the oil therein, means to admit shale into said distilling and cracking chamber, including a substantially air tight valve, and means to permit the discharge of spent shale and ash from said apparatus including a substantially air tight valve. 75

17. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and supplying the same to said shale to distill and 80 crack the oil therein, means to admit shale into said distilling and cracking chamber including a substantially air-tight measuring valve, means to permit the discharge of spent shale and ash from said apparatus including a substantially air tight measuring valve, and means to operate each of said measuring valves.

18. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and supplying the same to said shale to distill and crack the oil therein, means to admit shale into said distilling and cracking chamber including a substantially air tight measuring valve, means to permit the discharge of spent shale and ash from said apparatus including a substantially air tight measuring valve, and a connecting drive connection between 105 said valve adapted to maintain the movement of one valve constant with the movement of the other.

19. An apparatus for extracting hydrocarbon oils from shale and similar material and for treating the oils, which comprises a combined distilling and cracking chamber, a cooling chamber positioned as a continuation of said combined distilling and cracking chamber, means to admit shale into said distilling and cracking chamber, means for generating hot gases of combustion and supplying the same to said shale to distill and crack the oil therein, means for collecting and conducting condensed oil from said cooling chamber at a point relatively distant from the source of said gases of combustion and introducing said condensed oil into said distilling and cracking chamber at a point relatively adjacent the source of said gases 130

- of combustion, means for collecting and conducting condensed oil from said cooling chamber at a point relatively nearer the source of said gases of combustion than said 5 first point of collecting and introducing the same into said distilling and cracking chamber at a point farther away from the source of said gases of combustion than the first mentioned point of introduction, means to 10 admit shale into said distilling and cracking chamber including a substantially air tight valve, means to permit the discharge of spent shale and ash from said apparatus including a substantially air tight valve.
- 15 20. An apparatus for extracting hydrocarbon oils from shale and similar material and for treating the oils, which comprises a combined distilling and cracking chamber, a cooling chamber positioned as a continuation 20 of said combined distilling and cracking chamber, means to admit shale into said distilling and cracking chamber, means for generating hot gases of combustion and supplying the same to said shale to distill and 25 crack the oil therein, means for collecting and conducting condensed oil from said cooling chamber at a point relatively distant from the source of said gases of combustion and introducing said condensed oil into said 30 distilling and cracking chamber at a point relatively adjacent the source of said gases of combustion, means for collecting and conducting condensed oil from said cooling chamber at a point relatively nearer the 35 source of said gases of combustion than said first point of collecting and introducing the same into said distilling and cracking chamber at a point farther away from the source of said gases of combustion than the first 40 mentioned point of introduction, means to admit shale into said distilling and cracking chamber, including a substantially air tight measuring valve, means to permit the discharge of spent shale and ash from said 45 apparatus including a substantially air tight

measuring valve, and a connecting drive member between said valves adapted to maintain the movement of one valve constant with that of the other.

21. An apparatus for extracting hydrocarbon oils from shale and similar material and for treating the oils, which comprises an upright combined distilling and cracking chamber, a cooling chamber positioned as a continuation of said combined distilling and cracking chamber and immediately above the latter, means to admit shale into said distilling and cracking chamber, means for generating hot gases of combustion and supplying the same to said shale to distill and 60 crack the oil therein, means to admit shale into said distilling and cracking chamber including a substantially air-tight valve, and means to permit the discharge of spent shale and ash from said apparatus including a 65 substantially air tight valve.

22. An apparatus for extracting hydrocarbon oils from shale and similar material and for treating the oils, which comprises an upright combined distilling and cracking 70 chamber, a cooling chamber positioned as a continuation of said combined distilling and cracking chamber and immediately above the latter, means to admit shale into said distilling and cracking chamber, means for 75 generating hot gases of combustion and supplying the same to said shale to distill and crack the oil therein, means to admit shale into said distilling and cracking chamber including a substantially air tight measuring 80 valve, means to permit the discharge of spent shale and ash from said apparatus including a substantially air tight measuring valve, and a connecting drive member between said valves adapted to maintain the 85 movement of one valve constant with that of the other

In testimony whereof I have hereunto set my hand.

ROLAND B. DAY.
